PROJECTILE

William N. McGee, Seattle, Wash.

Application April 16, 1942, Serial No. 439,169

1 Claim. (Cl. 102—50)

This invention relates to improvements in projectiles and it has reference particularly to projectiles of those kinds or types designed to be fired from guns, both of large and of small caliber; it being the principal object of the invention to provide a projectile of an improved two-piece construction, whereby greater and sustaining velocity of the main body of the projectile is made possible and its penetrating ability thereby increased accordingly.

More specifically stated, the objects and advantages of the present invention reside in the provision of a projectile comprising a main body portion of novel form and equipped with a base section that facilitates the firing of the projectile but is immediately separable therefrom upon leaving the gun; the said main body portion being of an elongated cylindrical nature, tapered both at its forward and rearward ends, and formed with an open axial bore whereby compression or condensation of air at the nose of the projectile in flight is relieved and through which bore air is caused to flow to relieve any vacuum that might be created at the base of the projectile, thereby making possible the greater distance of flight, the greater velocity, and the consequent greater facility for penetration.

Still further objects of the present invention reside in the novel details of construction of the base section of the projectile; this being socketed to receive and conform to the tapered rear end portion of the projectile body, thus to operate substantially as a part thereof at the instant of firing the gun, but which immediately separates from the main body of the projectile after it has left the gun, thus to gain the advantages in the tapered ends and axial bore of the latter; the said base portion having a flat or concaved end surface against which the force of the firing charge is expended and whereon there is a peripheral sealing band designed to effect a tight gas seal with the gun barrel thus to insure the maximum results from the firing charge.

Still further objects of the invention are to be found in the details of construction of the base portion and main body of the projectile, and in their combination, as will hereinafter be fully described.

In accomplishing these and other objects of the invention, I have provided the improved details of construction, the preferred forms of which are illustrated in the accompanying drawing, wherein—

Fig. 1 is a side view of a projectile embodied by the present invention.

Fig. 2 is a longitudinal, sectional view of the projectile, showing the main body portion and the base portion separated from each other for purpose of better illustration.

5 Fig. 3 is a longitudinal, sectional view of a cartridge equipped with a projectile embodied by and in accordance with details of the present invention.

Fig. 4 is a cross sectional view, on the line 4—4

10 in Fig. 2.

Referring more in detail to the drawing—

In Figs. 1 and 2, I have illustrated the present type of projectile in its present preferred design for use in the ordinary types of large caliber 15 guns, such as those in which the firing charge is ordinarily separated from the projectile. In Fig. 3, the projectile has been illustrated as applied to a cartridge or shell which contains also a firing charge adapted to be ignited by a cap 20 that is arranged in the base of the cartridge and adapted to be struck by a firing pin.

Referring now more particularly to the construction of the projectile: This comprises the main body portion 1 and the base portion 2, each 25 of suitable, relatively hard metal as is well understood in the art to which this invention applies. The main body portion is of elongated, cylindrical form, and is gradually tapered at both its forward and rearward ends toward a point.

30 Formed lengthwise of and also coaxial of the main body 1 of the projectile, is a bore or passage 3, of substantial diameter, and, as will be noted by reference to Fig. 2, the outside surfaces of the tapered end portions of the body merge 35 into this bore in a thin edge. As herein indicated, the diameter of the bore is uniform, and is equal approximately to one-fifth the diameter of the shell body at its larger or medial portion, but the relationship might be varied somewhat

40 without departing from the spirit of the invention. It is desired, however, that a short length of the bore, at the nose or forward end of the projectile, be just slightly flared, as indicated at 5, in order to insure greater flow of air through 45 the bore from the forward to the rearward end of the projectile to break or prevent vacuum at the rearward end.

By reference to Fig. 3, in particular, it will be noted that the length of the tapered portions, 50 both at the forward and rearward end of the projectile, extend through about one-third the length of the projectile and the middle third of the projectile is uniformly cylindrical.

Formed about the medial portion of the projectile are two or more spaced rings 8—8 of

relatively soft metal. These are countersunk within grooves provided therefor in the body of the projectile, with their outer surface portions extended slightly beyond the surface of the projectile to engage with the rifling of the gun barrel, thus to effect the spinning or rotation of the projectile in flight as is common practise.

The base portion 2 of the projectile is about one-third the length of the assembled projectile, is truly cylindrical in form, and has a diameter corresponding to the diameter of the projectile body 1 at its medial portion. This base portion is formed with a flat rear end surface, and its forward end portion is formed with a tapered socket 9 corresponding to the shape of the tapered rear end portion of the projectile and adapted to seat the latter therein in a snug fit, with the rear end portion of the projectile resting solidly against the flat base surface 11 of the socket.

The side walls of the base portion 2 of the projectile are encased in a lining sleeve 12 of relatively soft metal. Also, the rear end surface is likewise faced with a sheet of soft metal indicated at 13. A rearwardly directed flange portion 14 is formed about the peripheral portion of the rear end surface of the base member, and this flange is designed to fit snugly against the bore of the gun barrel in such manner that when a firing charge is exploded, its force will cause the flange 14 to expand, thus to effect a tight, gas-sealed fit against the gun barrel. Also, the soft metal of the flange and sleeve 12 will embed the riflings of the barrel therein to cause the base portion 2 to rotate with the projectile body as it leaves the gun barrel.

The projectile, as illustrated in Fig. 3, is like that of Fig. 1 except that it is shown as being fitted in a cartridge, or shell 15. The side or cylindrical wall portions of the cartridge are clinched at their forward edges into an annular groove 16 of the projectile body to hold the parts properly assembled.

The firing charge 20 is illustrated in Fig. 3 as being contained within the cartridge between the base portion of the projectile and the base portion of the cartridge, and there is a firing cap 25 in the base of the latter.

Assuming the projectile to be so constructed, as in Fig. 1 or Fig. 3, it is apparent that whether

it be used in a gun of large caliber or of smaller caliber such as a rifle, its action and function will be the same. Immediately upon the exploding of the firing charge, the entire projectile will be forced within the gun barrel under the driving influence of the firing charge, the soft metal flange on the base of the projectile base will be expanded against the surface of the gun barrel to form the gas-tight seal. The soft metal rings of the projectile body and the soft metal lining of the projectile base will engage the riflings of the barrel to cause the spinning of the projectile in flight. However, as soon as the projectile has left the gun barrel, the projectile body 1 will free itself from the base portion 2 by reason of the air pressure against the base, and immediately the projectile body will leave the base portion by reason of the lesser resistance of air thereto. Where ordinarily there would be great pressure of air at the nose of the projectile, this will now be relieved through the axial bore, and will flow to the rear of the projectile, and there will relieve the vacuum that might otherwise be produced. It is apparent that the relief of vacuum at the rear of the projectile and the relief of condensation at the nose will result in greater velocity and thus make possible greater penetrating ability, which is much desired in present-day warfare.

Having thus described my invention what I claim as new therein and desire to secure by Letters Patent is:

A projectile of the character described comprising a base portion and a main projectile body; said body being formed about its medial portion with soft metal bands to engage the riflings of the gun barrel and having an open axial bore of substantial diameter therethrough for relief of air pressure at the nose and reduction of vacuum at the rear end of the projectile in flight, and having its forward and rearward end portions tapered to merge with the bore in sharp edges; said base portion of the projectile being of cylindrical form and of the diameter of the main body and formed with a socket in which the rear end of the projectile body is fitted, and having an encasing lining of soft metal of the diameter of the soft metal bands and said lining forming a rearwardly extending expandible peripheral flange.

WILLIAM N. McGEE.
